(57) **CLAIM**

The ornamental design for a decanter, as shown and described.

DESCRIPTION

FIG. 1 is a top, front and left side perspective view of a decanter showing my new design;

FIG. 2 is a bottom, rear and right side perspective view thereof;

FIG. 3 is a front elevational view thereof;

FIG. 4 is a rear elevational view thereof;

FIG. 5 is a bottom plan view thereof;

FIG. 6 is a top plan view thereof;

FIG. 7 is left side elevational view thereof;

FIG. 8 is a right side elevational view thereof; and,

FIG. 9 is a exploded isometric view of a decanter and its holder.

The broken lines showing of trigger in FIGS. 1, 2, 3, 4, 5, and 9, depicts portions of the decanter that form no part of the claimed design. The broken line showing of the decanter holder in FIG. 9 depicts environmental subject matter that form no part of the claimed design.
